UNITED STATES PATENT OFFICE.

WILLIAM H. NEWBROUGH, OF LANSING, MICHIGAN, ASSIGNOR TO THE "NEW WAY" MOTOR COMPANY, OF LANSING, MICHIGAN.

MULTIPLE-CYLINDER PUMP.

1,037,297.

Specification of Letters Patent. Patented Sept. 3, 1912.

Application filed January 29, 1912. Serial No. 673,990.

To all whom it may concern:

Be it known that I, WILLIAM H. NEWBROUGH, a citizen of the United States, residing at the city of Lansing, county of 5 Ingham, and State of Michigan, have invented certain new and useful Improvements in Multiple-Cylinder Pumps, of which the following is a specification.

This invention relates to improvements in 10 multiple cylinder pumps.

My improvements are especially designed by me for use in spraying machines where a light, compact pump is desired, and at the same time one capable of sustaining 15 high, uniform pressures, although it is desirable for use in various relations.

The main objects of this invention are, first, to provide an improved multiple cylinder pump which is very compact and one in 20 which the working parts are effectively balanced. Second, to provide an improved multiple cylinder pump which is simple and economical in structure and well adapted for high pressure service.

25 Further objects, and objects relating to structural details, will definitely appear from the detailed description to follow.

I accomplish the objects of my invention by the devices and means described in the 30 following specification.

The invention is clearly defined and pointed out in the claims.

A structure which is a preferred embodiment of my invention is clearly illustrated 35 in the accompanying drawing, forming a part of this specification, in which:

Figure I is a plan view of a structure embodying the features of my invention. Fig. II is a side elevation from the right of Fig. 40 I. Fig. III is a side elevation from the left of Fig. II. Fig. IV is a detail horizontal section taken on a line corresponding to line 4-4 of Fig. II, the bearing pedestals 3 and 30 being removed. Fig. V is a detail vertical section taken on a line corresponding to the 45 broken line 5-5 of Fig. IV, the base being omitted. Fig. VI is a detail vertical section taken on a line corresponding to line 6-6 of Fig. V, showing the arrangement of a 50 pair of the inlet valve casings.

In the drawing, similar reference characters refer to similar parts throughout the several views, and the sectional views are taken looking in the direction of the little 55 arrows at the ends of the section lines.

Referring to the drawing, the base 1 is in the form of a rectangular frame provided with feet 2 for the attachment of the base. A yoke-like pedestal 3 is mounted centrally on this base, the upper end of the pedestal being bifurcated as shown. The pump body is mounted on the base beneath the pedestal, the body being provided with a cylinder chamber 4 for each cylinder 7, an inlet conduit 5 and discharge conduits 6. The cylinders 7 are open at each end and provided with shoulders 8 adapted to support the cylinders in openings 9 provided therefor in the pump body so that the cylinders open 60 into the chambers 4. See Fig. V. The cylinders 7 are arranged in pairs with a cylinder of each pair at each side of the pedestal 3. The inlet 5 is arranged between the pairs of cylinders, while the discharge 65 conduits 6 are arranged on the outer sides thereof. Each cylinder chamber 4 is provided with inlet valves 10 and discharge valves 11. The valve casings for the inlet and the discharge valves are, in the structure illustrated, formed integrally with the pump body, as are also the conduits 5 and 6. The pump body is provided with feet 12, also formed integrally therewith, adapted to rest 70 upon the base. The supply pipe 13 is connected to the inlet conduit 5 as shown in Fig. VI, the supply pipe being arranged through one of the base side members whereby it is supported. The delivery pipe 14 is connected to both of the discharge conduits. 75

The details of the valves illustrated not being a part of this invention, are not described herein.

The pistons 15 are hollow to receive the 80 ends of the piston rods 16, which are connected by the pins 17 to the coupling members 18 which are bolted to the inner ends of the pistons. See Fig. V. To provide a simple and effective cylinder structure, the 85 cylinders are provided with internal annular recesses 19 at their outer ends adapted to receive the packings 20 and the packing glands 21. The flanged collars 22 are 90 threaded upon the cylinders to adjustably retain the glands 21. These collars serve 95 to support the upper ends of the pistons. The crank shafts 23 are provided with cranks 24 at their ends, there being a crank at each side of the pedestal. The piston rods 16 are connected to these cranks by 100 105 110

suitable crank pins. The driving shaft 25 is arranged between the crank shafts. The bearings 26 and 27 for the driving and crank shafts are mounted on the members or forks of the bifurcated pedestal. On each crank shaft is a gear 28, while the driven shaft is provided with a gear 29 meshing with both of the gears 28. The shaft 25 is further supported by the pedestal 30 mounted on one of the side members of the base 1. The cranks of each crank shaft are disposed oppositely so that the pumps of each pair are alternately actuated. The driving connections for the two crank shafts are arranged so that the cranks of one pair of pumps are, in their operative relation, at an angle of 90° to those of the other pair. This secures a successive work stroke for all of the pumps.

20 My improved pump is very compact although of large capacity. The working parts are effectively balanced and supported. The pump is well adapted for use in maintaining high pressures.

25 I have illustrated and described my improvements in detail in their preferred embodiment and not attempted to illustrate or describe the modifications possible as I believe the disclosure made will enable those skilled in the art to embody my improvements as conditions or taste may dictate.

Having thus described my invention, what I claim as new and desire to secure by Letters Patent is:

35 1. In a pump, the combination of the base, a bifurcated yoke-like bearing pedestal mounted thereon, vertically disposed open-ended pump cylinders arranged in pairs with a cylinder of each pair at each side 40 of said bearing pedestal, a pump body provided with a chamber for each cylinder, an inlet conduit, a pair of discharge conduits, the inlet conduit being disposed between the pairs of cylinders, the discharge conduits being disposed on the outer sides thereof, inlet and discharge valve casings connecting each cylinder chamber with said inlet and with one of the discharge conduits and supporting feet resting on said base, said 50 cylinder chambers, conduits, valve casings and feet being formed integrally, said cylinders being mounted on said body to open into said cylinder chambers, inlet and discharge valves arranged in said valve casings, 55 pistons, piston rods therefor, crank shafts having cranks at the sides of the pedestal, a driving shaft arranged between said crank shafts, connecting gears for said driving and crank shafts arranged between the 60 members of the pedestal, and bearings for said shafts mounted on the members of the pedestal.

2. In a pump, the combination of the base, a bifurcated yoke-like bearing pedestal mounted thereon, vertically disposed open-

ended pump cylinders arranged in pairs with a cylinder of each pair at each side of said bearing pedestal, a pump body provided with a chamber for each cylinder, an inlet conduit, a pair of discharge conduits, the inlet conduit being disposed between the pairs of cylinders, the discharge conduits being disposed on the outer sides thereof, inlet and discharge valve casings connecting each cylinder chamber with said inlet and with one of the discharge conduits, said cylinders being mounted on said body to open into said cylinder chambers, inlet and discharge valves arranged in said valve casings, pistons, piston rods therefor, crank shafts having cranks at the sides of the pedestal, a driving shaft arranged between said crank shafts, connecting gears for said driving and crank shafts arranged between the members of the pedestal, and bearings for said shafts mounted on members of the pedestal.

3. In a pump, the combination of the base, a bearing pedestal mounted thereon, vertically disposed open-ended pump cylinders arranged in pairs with a cylinder of each pair at each side of said bearing pedestal, a pump body provided with a chamber for each cylinder, an inlet conduit, a pair of discharge conduits, the inlet conduit being disposed between the pairs of cylinders, the discharge conduits being disposed on the outer sides thereof, inlet and discharge valve casings connecting each cylinder chamber with said inlet and with one of the discharge conduits, said cylinder chambers, conduits and valve casings being formed integrally, said cylinders being mounted on said body to open into said cylinder chambers, inlet and discharge valves arranged in said valve casings, pistons, piston rods therefor, crank shafts having cranks at the sides of the pedestal, and bearings for said shafts mounted on the pedestal.

4. In a pump, the combination of the base, a bifurcated yoke-like bearing pedestal mounted thereon, vertically disposed open-ended pump cylinders arranged in pairs with a cylinder of each pair at each side of said bearing pedestal, a pump body provided with a chamber for each cylinder, said cylinders being mounted on said body to open into said cylinder chambers, inlet and discharge conduits, inlet and discharge valves connecting each cylinder chamber with the inlet and discharge conduits, pistons, piston rods therefor, crank shafts at the sides of the pedestal, a driving shaft arranged between said crank shafts, connecting gears for said driving and crank shafts arranged between the members of the pedestal, and bearings for said shafts mounted on the members of the pedestal.

5. In a pump, the combination of the base, a yoke-like bearing pedestal mounted there-

- on, vertically disposed open-ended pump cylinders arranged in pairs with a cylinder of each pair at each side of said bearing pedestal, a pump body arranged under said pedestal and provided with a chamber for each cylinder, said cylinders being mounted on said body to open into said cylinder chambers, inlet and discharge conduits, inlet and discharge valves connecting each cylinder chamber with the inlet and discharge conduits, pistons, piston rods therefor, crank shafts having cranks at the sides of the pedestal, a driving shaft arranged between said crank shafts, connecting gears for said driving and crank shafts arranged between the members of the pedestal, and bearings for said shafts mounted on the members of the pedestal.
- 15 6. In a pump, the combination of the base, a bifurcated yoke-like bearing pedestal mounted thereon, vertically disposed pump
- cylinders arranged in pairs with a cylinder of each pair at each side of said bearing pedestal, pistons, piston rods therefor, 20 crank shafts having cranks at the sides of the pedestal, a driving shaft arranged between said crank shafts, connecting gears for said driving and crank shafts arranged between the members of the pedestal, and 25 bearings for said shafts mounted on the members of the pedestal.
- In witness whereof, I have hereunto set my hand and seal in the presence of two witnesses.
